UNITED STATES PATENT OFFICE.

MICHAEL A. GREEN, OF WHEELING, WEST VIRGINIA, ASSIGNOR TO HAZEL-ATLAS GLASS COMPANY, OF WHEELING, WEST VIRGINIA, A CORPORATION OF WEST VIRGINIA.

DESIGN FOR A CAP FOR BOTTLES OR SIMILAR ARTICLES.

Application filed June 3, 1927. Serial No. 22,309. Term of patent 7 years.

To all whom it may concern:

Be it known that I, MICHAEL A. GREEN, a citizen of the United States, residing at Wheeling, in the county of Ohio and State of West Virginia, have invented a new, original, and ornamental Design for a Cap for Bottles or Similar Articles, of which the following is a specification, reference being had to the accompanying drawing, forming part thereof.

The figure is a perspective view of a cap for bottles or similar articles, showing my new design, the flange thereof being indicated by dotted line.

I claim:

The ornamental design for a cap for bottles or similar articles, as shown.

MICHAEL A. GREEN.
